UNITED STATES PATENT OFFICE.

JOHN GOOD, OF NEW YORK, N. Y., ASSIGNOR TO JULIA E. GOOD, OF SAME PLACE.

FEEDING APPARATUS FOR MACHINERY FOR PREPARING FIBROUS MATERIALS.

SPECIFICATION forming part of Letters Patent No. 608,981, dated August 9, 1898.

Application filed January 19, 1897. Renewed June 3, 1898. Serial No. 682,505. (No model.)

To all whom it may concern:

Be it known that I, JOHN GOOD, of New York, (Far Rockaway,) in the county of Queens and State of New York, have invented a new and 5 useful Improvement in Feeding Apparatus for Machinery for Preparing Fibrous Materials for Spinning, of which the following is a specification.

The improvement which is the subject of 10 this invention is more especially applicable for the feeding of fibrous materials, such as sisal and other kinds of hemp the fibers of which are of considerable length, and it is applicable to any machines—such, for example, as spreading and drawing machines—in which such fibers are subjected to the operation of devices comprising pins by which the said fibers are subjected to a combing or hackling operation.

20 An apparatus embodying the said improvement consists of a table comprising bars armed with pins, means of moving the said table in one direction, a fiber-feeding carriage, and means for moving the said carriage back 25 and forth over the said table for the purpose of depositing the fibers thereon in layers one upon another, with the ends of the fibers of each layerlapping those of the layers above and below them; and the said improvement 30 consists in certain combinations hereinafter described and claimed, of which such table and carriage constitute elements.

In the accompanying drawings, Figure 1 is 35 a side view of a feeding apparatus embodying my invention. Fig. 2 represents a central longitudinal vertical section, and Fig. 3 a plan view of the same; Fig. 4, a side view showing some of the details on a larger scale than Fig. 1.

40 Similar letters and numerals of reference designate corresponding parts in all the figures.

A is the framing on or in which are the 45 bearings for the shafts *a* *b*, which carry the wheels *c* *d*, on which run the endless chains *B*, which carry the transverse bars *e*, which are armed with gill-pins *f*. These shafts, chains, wheels, bars, and pins may be of any known or suitable construction such as is 50 common to spreading and drawing machines, and they are represented of well-known con-

struction, the bars in the upper run of the chains forming a platform or table from which the pins *f* project upward. The said chains and the train of bars and pins are 55 driven by any suitable means at a very slow speed in the direction of the arrow *21*. (Shown in Fig. 2.) I have represented for this purpose on the shaft *b* a spur-gear *s*, which is to receive motion from any suitable source of 60 power.

On the sides of the framing *A* are ways *G*, which extend from points forward of the chain-wheels *d* backward some distance beyond the rear of the said chains, the said ways 65 being parallel both vertically and laterally with the table or platform constituted by the straight upper run of the said chains and their bars *e* and pins *f*. On these ways *G* run a carriage *D*, in which is mounted the axle *E'* of a reel or lantern-wheel *E*, which extends across the chains *B*. The height of this reel above the ways and the spacing of its rungs *t* are such that the rungs will enter between the rows of pins in the bars of the upper run of 70 the chains *B* and press upon a bed of fiber imposed on the said bars, and that as the carriage *D* is moved back and forth on the ways the reel may be caused to rotate by the contact of its rungs with the said pins. The axle *E'* of the reel is so mounted in its bearings in 75 the carriage that the reel may be capable of a sufficient rise and fall to accommodate itself to the thickness of the bed of fibers on the bars *e*. The mechanism for producing the 80 backward-and-forward movement of the carriage to roll the reel over the pins *f* may be of any suitable kind. Of the mechanism which I have represented for that purpose, *H* is a right and left hand threaded endless 85 screw the shaft or core of which is fitted to turn freely, but confined lengthwise, in fixed bearings *u* on the frame *A*. This screw, which is parallel with the ways *G*, is fitted with a switch-nut *I*, which, by the continuous rotation of the screw in one direction, is caused 90 to run back and forth upon the right and left hand threads. The said nut *I* is connected with the carriage *D* by a rod *J*. The screw *H* is represented as furnished with a pulley 95 *v*, through which it is to be driven by a rapidly-running belt *w*. The speed at which the 100

carriage and the feed-board and reel are caused to move back and forth will be several times faster than that of the chains B and the pins f. The range of movement of the carriage is such as to carry the reel forward to about a position nearly over the forward end of the upper run of the chains B, as shown in full outline in Fig. 2, and backward to a position some distance beyond the chains, as shown in dotted outline in the same figure.

The carriage D is represented as having a counterbalance-weight K connected with it by a cord K' running over guide-pulleys K². This counterbalance is only rendered necessary when the chains and the carriage D are arranged to run at an inclination, as shown in the drawings, the counterbalance counter-acting the tendency of the carriage to run downward; but this inclination of the chains and bed is not essential to my invention, which would be just as well applicable in connection with chains the upper runs of which were horizontal, in which case the carriage would run horizontally.

Just behind the reel E there is arranged upon the carriage D a rising and falling or tilting feed-board F, which constitutes the principal feature of the present improvement. This feed-board is pivoted at its lower and forward end by a shaft F', which works in bearings 10 on the sides of the carriage. The said shaft F' serves no other purpose than as a pivot for the upward movement of the feed-board to the nearly upright position shown in full outline in Figs. 1 and 2, and its downward movement to the nearly horizontal position shown in dotted outline in the same figures, in which latter position it is supported upon a rest F³, affixed to the carriage. In either of these positions the lower or front end of the feed-board is high enough to pass over the pins f. A little way behind the said shaft F' a rock-shaft R is arranged in bearings 11 on the sides of the carriage D. This rock-shaft carries an arm R', on the end of which is an antifriction-roller 12, upon which the feed-board F bears, the purpose of the said rock-shaft and arm being to tilt the feed-board from the rest F³ to the nearly upright position, and thereby to deposit upon the pin-bars the bunches of fibers which are placed upon the feed-board while it is in the nearly horizontal position. The said rock-shaft R is furnished outside the frame with a spur-gear 13, (see Figs. 1, 3, and 4,) which gears with a spur-gear 14, turning loosely on a fixed stud 15, secured on the top of the carriage. On the same stud 15 there is loosely arranged a tappet 16, which when turned in the direction of the arrow shown in Fig. 4, by running against a fixed stop-pin 18 on the side of the framing A, is brought into action on a tappet-piece 17, affixed to the spur-gear 14, and turns the gear 14 in the same direction and so causes the latter to turn the gear 13 and the rock-shaft R in the opposite direction, and thereby to raise the arm R' against the feed-board and so tilt

the said board to the nearly upright position. The tappet-piece 17 is extended backward in the form of a guard 17* to overlap the tappet 16 and protect it from lateral displacement. The rock-shaft R is furnished outside of the framing A with an arm, on which is a counterbalance R² to the weight of the arm R' and the feed-board. The rest F³ is furnished at the top with an india-rubber cushion 22 to prevent any violent concussion of the feed-board when it drops thereon.

This feeding apparatus is placed behind any suitable device for combing, spreading, or drawing fibers—as, for example, an endless train of pin-armed bars—and so placed its operation is as follows: An attendant takes in his hands a bunch of raw fibers—such, for example, as the bunches in which the raw hemp comes in bales to the market—and while the feed-carriage D, with the feed-board F and reel E, is moving forward in the direction of the arrow 19, (shown in Figs. 1 and 2,) the feed-board being in its nearly horizontal position on the rest F³, he places the fibers lengthwise along the board and spreads them to some extent across the same and leaves them there. As long as the carriage continues moving forward or in the same direction with the upper run of the bars e and pins f the feed-board remains in this position, the tappet 16 swinging back and passing freely over the stop 18 on the framing without producing any action on the gear 14; but after the carriage has moved backward in the direction of the arrow 20 a very short distance the tappet 16, coming in contact with the pin 18, is turned toward and against the tappet-piece 17 on the said gear 14, and so, as the carriage continues moving backward, turns the said gear 14 in the direction of the arrow shown upon it in Fig. 4, thereby turning the gear 13 and the rock-shaft R in the opposite direction and raising or tilting the feed-board. While the feed-board is thus being tilted the fibers are shot or run freely by their own weight down the feed-board and so bring their forward ends under the reel E, which, being turned in the direction of the arrow shown upon it in Figs. 1 and 2, by its rungs coming in contact with the pins f as the backward movement of the feed-carriage continues, is caused to draw the fibers from the board and to deposit them upon the pins f. When the carriage has run some distance backward, the tappet 16 escapes from the pin 18, and the feed-board drops again to the rest F³; but this does not interfere with the drawing of the fibers therefrom and depositing them as hereinabove described. This operation is repeated during every movement of the carriage backward, and the successive bunches of fiber are thus superposed in several layers upon and between the pins f and upon the bars e; but as the chains B, with the said bars and pins, are continuously moving forward at a speed much slower than that of the carriage the several layers are superposed each some distance

behind the next layer below, and so the ends of the fibers of the several layers overlap or break joint with each other, as indicated at 6789 in Fig. 2. Thus in the very act of feeding the raw material it is so placed as to effect in a very considerable degree the essential object aimed at in all machinery for preparing fibrous materials—viz., the distribution of the ends of the fibers at numerous points in the length of the lap or sliver to be produced.

What I claim as my invention is—

1. The combination of a table comprising bars armed with pins, means for moving said table in one direction, a carriage and means for moving the same back and forth over said table, a tilting feed-board on said carriage, and means for tilting said feed-board, substantially as herein described.
2. The combination of a table comprising bars armed with pins, means for moving said table in one direction, a carriage and means for moving the same back and forth over said table, a reel on said carriage, a tilting feed-board on said carriage in rear of said reel, and means for tilting said feed-board, substantially as herein described.
3. The combination substantially as herein set forth of a table comprising bars armed

with pins, means for moving said table in one direction, a carriage and means for moving the same back and forth over said table, a tilting feed-board pivoted at its front end to said carriage, and means substantially as herein described for tilting said board automatically by the backward movement of the carriage.

4. The combination of a table comprising bars armed with pins and means for moving the said table in one direction, a carriage and means for moving the same back and forth over said table, a tilting feed-board pivoted at its front end to said carriage, a rock-shaft on said carriage for tilting the rear end of said feed-board, a gear on said rock-shaft, a stud on said carriage, a loose gear on said stud gearing with said gear on the rock-shaft, a loose swinging tappet on said stud for turning said loose gear in one direction, and a fixed stop for actuating said tappet to produce the tilting of the feed-board during the backward movement only of the carriage, all substantially as herein described.

JOHN GOOD.
